[57] CLAIM

The ornamental design for an immersible pool side chair, as shown and described.

DESCRIPTION

FIG. 1 is a left side elevational view of the immersible pool side chair of the present invention;

FIG. 2 is a right side elevational view of the immersible pool side chair of FIG. 1;

FIG. 3 is a front elevational view of the immersible pool side chair of FIG. 1;

FIG. 4 is a back elevational view of the immersible pool side chair of FIG. 1;

FIG. 5 is a top plan view of the immersible pool side chair of FIG. 1; and,

FIG. 6 is a bottom plan view of the immersible pool side chair of FIG. 1.

The fragmented cross-hatching shown on the seat member in FIGS. 3 through 6 is understood to represent fabric and would be continuous throughout the implied areas.
